MAX PARNASS, OF NEW YORK, N. Y., ASSIGNEE OF ONE-HALF TO ISIDOR I. ZEEMAN,
OF NEW YORK, N. Y.

GARMENT-BAG.

1,203,042.

Specification of Letters Patent.

Patented Oct. 31, 1916.

Application filed January 26, 1916. Serial No. 74,332.

To all whom it may concern:

Be it known that I, MAX PARNASS, a citizen of the United States of America, residing in the borough of Manhattan, city, county, and State of New York, have invented certain new and useful Improvements in Garment-Bags, of which the following is a specification.

My invention relates to garment bags adapted to receive a clothes hanger of the usual type, and to protect the clothes while they are suspended from said hanger on a hook, and at the same time to provide a construction of bag which may easily be placed upon the garments while on the coat hanger or removed therefrom.

A further object of my invention is to provide a construction of garment bag that will be simple and economical in construction, that will not waste material and will therefore be economical in material, and a further and important object is to provide a construction which will effectually prevent the entrance of dust into the garment bag.

A desirable form in which my invention may be embodied is illustrated in the accompanying drawing wherein,

Figure 1 is a perspective view of my improved garment bag. Fig. 2 is a longitudinal section on the line 2-2 partly broken. Fig. 3 is a plan view of the blank or pattern from which my garment bag is made; and Fig. 4 is a cross section of Fig. 1 on the line 4-4 looking in the direction of the arrows, partly broken.

The improved garment bag invented by me has for its very important objects to produce a garment bag which will effectually screen the garments contained therein from dust, and which is easily applied to or removed from the garments while on the coat hanger which will be so economical in material and construction that it can be produced and sold at a price that will make it an object of general use. In carrying my invention into effect I have therefore provided a garment bag wherein the pattern or blank is formed in one piece, as illustrated in Fig. 1. It may be made of any desired cheap and flexible material such as paper or cloth, but I prefer to make it of a cheap grade of cloth which excludes dust from passing through the body such as the cheaper grades of lining cloth. The pattern as illus-

trated in Fig. 3 is formed of a single piece of material A. This is bent upon the line B so that the two sides C, D are folded one upon the other. The bottom edge E is permanently closed by the cloth. The lefthand edge F as illustrated in Fig. 1 is also permanently closed by being sewed or seamed together. A portion G of the top edge is also permanently closed by being sewed or seamed together. Upon the side C and on the edge opposite the closed edge F the material extends to form a flap H, and this flap H is bent around the line I to close the said edge. Upon a top edge of one of the sides, and preferably upon the top edge of the opposite side D, material is likewise left to form a second and top flap J which closes the portion of the top edge that is left open. This top flap J is bent around the line K to close the said edge. Both the side flap H and the top flap J are secured in closed position by separable retaining devices such as the ordinary snap or glove fasteners L, of which three are illustrated as employed for the purpose of securing the side flap to the side D, and one for the purpose of securing the top flap J to the side C.

It will be apparent that in constructing my invention from a single piece of cloth one of the edges E or F may be permanently closed by sewing, and the other may be closed by the material. I prefer the arrangement shown wherein the longitudinal edge F is the one closed by sewing as I believe this is more economical in material. The edges F and G are stated to be permanently secured together by sewing, and this is obviously preferable in case the bag is made of cloth, although in this case for particularly cheap construction pasting might be feasible, and if the bag were made of paper it would probably be preferable to paste the side edges together.

The clothes are held in the garment bag by being suspended from the ordinary clothes hanger M which customarily has a hook m, the shank of which passes through the opening in the top of the bag between the closed seam G and the flap J.

It will be apparent from the foregoing description that my garment bag is one which may be easily applied to or removed from the clothing. The hook m may, if desired, be retained upon the rod or other means from which it is suspended, and the

2
 top and bottom flaps opened whereupon the clothes may easily be slipped off of the clothes hanger if desired without removing the same from the clothes hanger, or if preferred the bag, when the flaps are opened, may easily be slipped off from the garments and as easily replaced. I prefer to form the flap H so that the same will be folded against the side opposite to that against which the flap J is folded as thereby a better closure is obtained, and a more secure sealing against the dust.

10 I have illustrated the most desirable manner of constructing my invention known to me, but the same may be modified within the limits of the foregoing description and of the appended claims.

What I claim is:—

1. A garment bag formed of a single piece of material having its bottom edge, one side edge and a portion of the top edge permanently closed, and having a flap formed on one side opposite said closed edge, and having a flap formed in a portion of

one side at the top edge, said side and top flaps adapted to be bent around their respective edges and separable retaining devices for holding said respective flaps in closed position.

2. A garment bag formed of a single 30 piece of material having its bottom edge, one side edge and a portion of the top edge permanently closed, and having a flap formed on one side opposite said closed edge, and having a flap formed in a portion 35 of the opposite side at the top edge, said side and top flaps adapted to be bent around their respective edges and separable retaining devices for holding said respective flaps in closed position.

40 In witness whereof, I have hereunto signed my name in the presence of two subscribing witnesses.

MAX PARNASS
